ADJUSTABLE FLOATING ROOF

Alexander F. Fino, Warren, Pa., assignor to Hammond Iron Works, Warren, Pa., a corporation of Pennsylvania

Application November 19, 1956, Serial No. 622,865

4 Claims. (Cl. 220—26)

This invention relates generally to storage tanks for liquids and more particularly to tanks for storing oil products wherein there is employed a roof or cover which floats on the liquid stored in the tanks to rise and fall with the level of such liquid.

In tanks of the type referred to, a space is present around the periphery of the floating roof and the tank wall which must be kept closed or sealed at all times during the movement of the roof with the changing level of the liquid on which it floats and, it is accordingly, an object of the present invention to provide in a manner as hereinafter set forth a new and improved roof construction whereby the maintenance of such a seal between the outer part of the roof and the wall is effected.

Tanks of the character stated are of relatively large diameter and accordingly the inner periphery of the tank wall against which the seal carried by the floating roof engages is seldom of a true circular form and usually has many other and substantial irregularities. It is accordingly a further object of the invention to provide an improved floating roof structure which will automatically adjust itself to such irregularities so as to maintain the desired sealing engagement with the tank wall.

Still another object of the invention is to provide a floating roof structure wherein there are a number of radially shiftable coupled sections with means at the central portion of the roof for controlling the radial movements of the sections as the roof rises and falls and as it passes over irregularities in the circular contour of the wall so that such sections will maintain desired sealing contact at their outer edges with the tank wall regardless of the variations in the circular contour thereof.

Still another object of the invention is to provide an adjustable floating roof structure which will automatically adjust itself to any diameter of the tank in which it is disposed, within reasonable limits.

Still another object of the invention is to provide an adjustable floating roof structure embodying in association with a circular central section a plurality of radially extending sectors having interengaging sealing contact one with the other between adjacent radial edges and having a novel connection at their inner ends with the central section whereby the radial movement of the sectors is caused to take place as the interior diameter of the tank varies or as the sectors pass over irregularities therein whereby to maintain in constant sliding engagement with the inner surface of the tank a sealing means carried by the outer ends of the sectors.

Still another object of the invention is to provide a floating roof construction of the character above described, which is formed of a relatively light material such as a suitable plastic which will be unaffected by the liquids in the tank and which has a substantial strength to maintain its form and position, which embodies in its construction a material giving it buoyancy sufficient to prevent its sinking in the liquid on which it is designed to float.

A still further object of the invention is to provide an adjustable floating roof construction which is not only de-

2

signed in a novel manner to permit the radial movements of the plurality of sectors with respect to a central circular section around which they are disposed so as to automatically adjust itself to variations in the diameter

5 of the tank but which is designed so that such sectors will maintain a sufficient degree of inclination to effect the movement of condensate outwardly to the periphery of the roof for drainage through the seal against the shell of the tank.

10 As this invention may be embodied in several forms without departing from the spirit or essential characteristics thereof, the present embodiment is therefore illustrative and not restrictive, since the scope of the invention is defined by the appended claims rather than by the 15 description preceding them, and all changes that fall within the metes and bounds of the claims or that form their functional as well as conjointly cooperative equivalents, are therefore intended to be embraced by those claims.

The invention is illustrated in the accompanying drawings 20 wherein one embodiment of the invention has been chosen for illustrating, but not for limiting, purposes.

In the drawings:

Fig. 1 is a vertical sectional view through a conventionally illustrated tank structure shown in perspective and 25 illustrating in perspective therein a floating roof structure constructed in accordance with the present invention in diametrical section, the roof sections being shown adjusted to the tank diameter to have a slight degree of slope;

30 Fig. 2 is a view in top plan of the roof structure, a portion of the same being broken away;

Fig. 3 is a top plan view on an enlarged scale of a number of the sectors detached from the central section;

Fig. 4 is a sectional view taken substantially on the 35 line 4—4 of Fig. 3;

Fig. 5 is a sectional view on a vertical plane diametrically through the central section of the roof, the view being on an enlarged scale;

Fig. 6 is a top plan view on an enlarged scale of the 40 central section with a portion broken away;

Fig. 7 is a sectional view on an enlarged scale taken substantially on the line 7—7 of Fig. 2;

Figs. 8, 9 and 10 illustrate diagrammatically the different positions of the roof sectors with relation to varying 45 diameters of the tank wall.

Fig. 11 is a top view of one sector only, with the middle portion broken out, and showing in dotted lines the boundaries of the chambered foam-glass filled section and the thickened end portions through which the slot extends.

Fig. 12 is a section taken substantially on the line 12—12 of Fig. 11.

Referring now more particularly to the drawings, the 50 numeral 16 generally designates a storage tank having a cylindrical vertical wall 12 and bottom 14 and in which is illustrated an adjustable floating roof structure generally designated 16 constructed in accordance with an embodiment of the present invention.

The roof structure comprises a central section or member 55 which is generally designated 18 and this central section embodies a frusto conical central part or wall 20, a head plate 21 which is secured to the top of the wall 20, and a bottom plate 22 which is secured across the bottom of the frusto conical wall. The head wall and bottom wall may be of approximately the same diameter as illustrated and this diameter is greater than the diameter of the base portion of the frusto-conical wall so that the bottom plate 22 extends slightly beyond the periphery of the bottom of the wall 20 and this bottom wall and the 60 head wall are provided with aligned openings 23 and 24 respectively for the purpose hereinafter set forth.

The central section as thus described provides a closed

chamber 25 which is filled with a suitable lightweight buoyant material which will have a buoyant effect in petroleum liquids, foam glass being one example of such material which might be employed.

The frusto-conical wall 20 of the central section provides a circular inclined surface or face 27 which functions as a camming surface in association with the hereinafter described sector portions of the roof.

Disposed around the central section 18 of the roof structure is a plurality of sector members each of which is generally designated 28. These sector members are preferably molded from a resin material such as polyester resin or any other suitable form of rigid plastic which can be molded and these sectors are molded to provide the top wall 29 and an underneath chamber or compartment-forming part consisting of a bottom wall 30 and convergent side walls 31 and 32.

The outer end edge 33 of the top wall of each of the sectors 28 is of a curvature to conform to the curvature of the inside surface of the tank wall 12.

The inner end edge 34 of each of the sectors is formed on a concave curvature and conforms to the curvature of the frusto-conical wall 20 of the central section with which it contacts when the sector is assembled with the center section in a manner hereinafter described.

The chamber 35 formed on the underside of the wall 29 of each sector terminates at the inner and outer ends of the sector wall 29 as indicated at 36 and 37, short of the end edges of the wall 29 and the portion 38 of the wall 29 extending beyond the inner end of the chamber 35 is provided with an elongate slot 39 which is directed longitudinally of the wall 29 or radially of the roof structure.

Extending along one side of each of the sectors, as for example along the side 32, referring to Fig. 4, is an outwardly projecting tongue 40. This tongue extends the full length of the sector and where it extends beyond the ends of the chamber 35 the wall 29 is thickened for strength and to carry the flange, as indicated at 40a.

At the opposite side of each sector from the tongue 40 there is provided the longitudinally extending groove 41 which is of a size to receive a tongue 40 of an adjacent sector. The groove 41 terminates at the ends of the chamber 35.

The chambers 35 of the sectors 28 are also filled with a buoyant material of the character hereinbefore referred to. In the construction of the sectors from the selected plastic, the plastic material is molded around the body of buoyant material which is designated 42 so that there is a firm bond effected between the material and the plastic material of which the sector walls are made.

The roof sectors 28 are assembled around the central section 18 with the tongues 40 engaged within the grooves of adjacent sectors and the curved inner end edges are disposed against the frusto-conical wall 20 of the center section with the slot 39 of each sector in line with and between two openings 23 and 24 of the head and bottom walls of the center section and a retaining pin or bolt 43 is passed through the aligned openings 23 and 24 and through the slot 39 of the interposed end of the roof sector as illustrated in Fig. 1. The length of the slots 39 is such as to permit the movement of the inner ends of the sectors to the full extent permitted by the space between the head wall 21 and bottom wall 22 of the center section so that in the functioning of the adjustable roof as it rises and falls with the changing level of liquid in the tank 10, the sectors may move radially toward and away from the encircling tank wall as required.

For keeping the slots 39 closed, each sector has disposed for sliding movement upon the top thereof over the slot, a cover plate 39a through which the bolt or pin 43 extends with sufficient freedom to permit the plate to slide smoothly thereon. Also the plate is of sufficient length to cover the slot when the pin is in either end of the slot.

In the complete assembly of the center section and the sectors, the overall diameter of the disc thus obtained is materially less than the inside diameter of the tank so that there remains between the outer edges 33 of the sectors and the tank wall 12 a space as indicated at 44 in Fig. 1.

The space 44 is maintained closed in all positions of the floating roof in the tank by means of a resilient sealing band 45 secured around the periphery of the roof. 10 This sealing band may be of any desired character and is here shown as being made up of a series of rubber wipers 46 each of which is secured by stapling as at 47 or in any other suitable manner to the top of the wall 29 of a sector to project radially outwardly therefrom. 15 The radial width of the wipers is such that in any of the positions to which the floating roof may move in the tank, a firm wiping engagement will be maintained between the outer edge 48 and the tank wall. This wiper is, of course, resilient so that it may bend or flex as required to conform to the different irregularities of the tank and to facilitate such bending or flexing, the outer portion of the wiper may be reduced in thickness or tapered off as indicated at 49 in Fig. 7.

The length of the wiper strips is somewhat greater than 25 that of the arcuate edges of the sectors to which they are secured and each strip is secured to the sector to have the extra length thereof extend beyond the grooved side of the sector, as indicated at 46a, in Figs. 1 and 2. When the roof sectors are assembled, each extended end 30 46a is positioned for sliding movement on the top of the adjacent strip 46. Accordingly, when the roof diameter increases so that the sectors separate any space occurring between the outer ends of the sectors will be kept covered.

In the operation of the roof structure, the adjustment of the center circular section is the key to the automatic functioning of the roof to adjust itself to any tank diameter within reasonable limits. The roof would be designed for a tank of a certain standard diameter with the length of the radial sections long enough that it cannot adjust to its normal displacement without forcing down the center circular section 18. For example, Fig. 40 8 illustrates the normal displacement of the sectors and if the tank shell becomes smaller in diameter by one or 45 two inches during the course of travel of the roof, the radial sections or sectors will slide upward at their inner ends on the circular sloping surface 27 of the frusto-conical wall 20 as illustrated diagrammatically in Fig. 9. Additional displacement of the center section will occur 50 but being free for movement, binding cannot occur. Likewise, on descending or downward movement of the inner ends of the sectors, as the tank wall or shell becomes larger than the standard neutral diameter, the radial sectors will be forced toward the shell or wall as 55 the roof section tends to level to its proper displacement. This adjustment will take place continuously and automatically for each of the sectors and will tend to seal localized buckles and irregularities in the form of the tank wall.

60 Fig. 10 illustrates maximum radial displacement where the sectors are substantially horizontal while Fig. 9 illustrates the minimum radial displacement where the sectors may have a slope of approximately 2½ degrees while in the neutral position of the sectors shown in Fig. 8, the sectors have a slope of approximately 1 degree.

In automatically adjusting itself to irregularities of the tank wall, the radial movements of the sectors do not have to be simultaneous or in unison.

From the foregoing description it will be readily apparent that there is provided by the present invention a new and novel floating roof structure which will automatically adjust itself to conform to changes in the contour of the tank wall in which the roof is positioned, as the liquid in the tank rises and falls thereby maintaining 70 at all times the desired sealing of the space 44 between

the outer part or periphery of the wall of the roof and the wall of the tank.

By forming this floating roof of plastic and buoyant material in the manner illustrated and described, a light weight but very strong and rigid construction is obtained.

Further, by the provision of a floating roof structure formed substantially throughout of plastic or other material of a non-metallic nature, such roof may be easily installed in existing tanks without danger of fire resulting from sparks such as might occur in handling metallic roof structures and metallic objects for installing such structures.

I claim:

1. A floating roof construction for installation in a tank having a vertical cylindrical wall comprising a central section having a downwardly and outwardly extending middle part, a circular head wall upon the top thereof and a circular bottom wall with the latter two being concentric with and of greater diameter than the base of the middle part, while the middle part provides a circular sloping wall, a plurality of sector shaped outer sections in side-by-side relation around and extending radially from the middle part of the central section with their inner ends between the head and bottom walls while having sliding sealing engagement with the sloping wall, means for retaining the inner ends of the sectors between the head and bottom walls while permitting limited radial movement of the sectors, means forming a sealing coupling between the adjacent sides of the sectors, and yieldable elastic sealing means encircling the roof while joined to the outer ends of the sector sections, wherein said means for retaining the inner ends of the sectors between the head and bottom walls comprises pins extending between the head and bottom walls and passing through radially extending slots in the said inner ends of the sectors.

2. A floating roof construction including a central section and a plurality of sector-shaped members movably secured thereto, each sector member comprising a hollow floatable chamber including a top, bottom and side and end walls, said side and end walls secured to the under face of said top wall inwardly of the terminal ends thereof and converging toward said bottom wall, floatable material completely enclosed in said hollow chamber, flange means formed integral with said top wall in the same plane as said top wall and extending inwardly from the terminal edges of said top wall to a point adjacent the juncture of said side and end walls with the underside of said top wall, said central section being of greater thickness than the sector members and having a downwardly and outwardly sloping peripheral

side wall engaging said innermost flange means of each sector to urge same outwardly, vertically extending rod means secured to said central section, said innermost flange means of each sector being movably secured to said rod means to retain the sectors in position and permit relative horizontal and vertical movement therebetween, and wiper means secured to the outermost flanges of each sector to form a seal between the sector flanges and the side walls of the receptacle in which the floating roof is positioned.

3. A floating roof construction as defined in and by claim 2 wherein said floatable material comprises a light-weight cellular material, and having an external shell of plastic material completely enclosing the cellular material in bonded relationship therewith.

4. In a liquid storage tank having a wall, a roof construction floating on the liquid to rise and fall with changes in the liquid level having a conical buoyant center section, a series of buoyant sector bodies extending radially from the center section and constituting a floating ring around the center section substantially occupying the annular space between the center section and the tank wall while being dimensioned to maintain edgewise contact at their inner ends upon the conical face of the center section and thereby assuming a slight downward outward inclination, said sector bodies adjusting themselves to irregularities of the tank wall as the level falls and rises by undergoing corresponding variations of their inclination accompanied by corresponding changes of immersion of the center section with the sector sections shiftable relative to one another and their inner ends moving up and down the conical face of the center section, vertical guide means carried by said center section and effective to provide for limited radial as well as up-and-down movement of each of the inner ends of respective sector bodies while substantially preventing lateral displacement thereof, said guide means having a bottom flange and a top flange provided upon said center section, and a guide pin extending between said flanges for each sector body and passing through respective radially-extending slots in the inner ends of the sector body.
